JAMES PETER KIMBLE, OF WHAT CHEER, IOWA.

REINFORCED-CONCRETE POST.

1,137,982.

Specification of Letters Patent.

Patented May 4, 1915.

Application filed May 19, 1914. Serial No. 839,613.

To all whom it may concern:

Be it known that I, JAMES P. KIMBLE, residing at What Cheer, in the county of Keokuk and State of Iowa, have invented a new and Improved Reinforced-Concrete Post, of which the following is a specification.

My invention is an improved concrete post of a construction especially designed for the employment of an anchoring member of a special construction which forms one of the essential parts of the invention.

In its more detail nature, the invention includes those novel details of construction, combination and arrangement of parts, all of which will be first fully described, then be specifically pointed out in the appended claims, and illustrated in the accompanying drawings, in which:

20 Figure 1 is a perspective view of my improved reinforced concrete post, the plastic body portion being indicated in faint lines to the more clearly illustrate the construction and arrangement of the reinforcing and anchoring elements. Fig. 2 is a horizontal section thereof on the line 2-2 on Fig. 1. Fig. 3 is a similar view on the line 3-3 on

Fig. 1. Fig. 4 is a perspective view of a portion of one of the sections of the "anchor device" hereinafter referred to. Fig. 5 is a vertical section of a portion of the said anchor device with the wire staples or holders in place thereon. Fig. 6 is a detail view of a slightly modified form of the staple sockets in the anchor device.

35 In my improved reinforced concrete post, (the general construction of which is clearly shown in Fig. 1, of the drawings,) 1 designates the plastic (concrete) body of the post, 40 which is molded upon the reinforcing elements and the anchoring device presently fully described, in the manner to be herein-after explained in detail.

The reinforcing elements consist of a plurality of vertically extended members, which may be of any desired number, but preferably three, arranged in triangular position, two of such members, designated 2-2, being located near the corners of the front 50 face 10, of the post, while the other or rear one 3, is located near the back face of the post body and centrally thereof as is clearly shown in Fig. 2.

The front members 2-2 are formed of two wire strands twisted about each other, while the rear one 3 of the said members is

formed of a greater number of twisted strands to give it the strength necessary to stand the strain thereon.

The several reinforcing members 2-2 and 3 are braced by horizontal bracing or binder members, as many of which are utilized as the particular size of the post may require, the purpose of such bracing or binder members being to provide the desired rigidity or reinforcement for the post body, and all of the said binder or bracing members, except the one next to the ground line, may be in the nature of a single wire strand 5, that is twisted about the front and end vertical members 2-2 and 3, and whose free ends extend inwardly from the front members 2-2 and engage with the anchoring device presently again referred to. The lower ends of each of the vertical members 2-2 and 3 are bent to form lateral extensions 20-30, and the said extensions form holds for conveniently handling the said members 2-2 and 3 in shipping, they also form interlocking members, since they are laterally embedded in the concrete body when the plastic material is poured into the mold, as hereinafter explained.

The binder or bracing member 50, located at the ground line of the post, is made of two or more wire strands twisted about each other, and the said binder 50 is twisted about the vertical members 2-2 and 3, is wound about the lower end of the anchor device and has its ends joined to each other, the same forming, as it were, an endless horizontal bracing member. By reason of making the bracing member 50 as stated and locating it at the ground line of the post, additional strength is added to the post at the base or ground line thereof where the greatest strain on the post exists, and to still further increase the stability of the post, at the said ground line, the binder or brace 50 is of somewhat larger size than the other or upper binders 5, to thereby bulge the said members 2-2 and 3 outwardly, to give them a trussed effect.

The anchoring device, the construction of which and its co-operative connection with the reinforcing elements form an essential feature of my invention, is formed of two metal half section plates 6-6 whose upper and lower ends, at the front edges thereof, are cutaway to form shoulders 60-61, the lowermost one 61 serving as a means for positively holding the wrapped part 56 of

the binder or brace 50 in a proper clamped connection with the anchor, the upper shoul-
dered portion 60 permitting, as it were, a proper shaping or filling of the upper end
5 of the plastic body 1, see Fig. 1.

To provide for a positive embedding of the anchor and for the desired lateral brac-
ing of the front reinforced members 2—2, the ends of the braces 5 are projected
10 through apertures 62 in the members 6, the said ends being bent to form shoulders 63 for bearing against the sides of the anchor, the latter also having vertical ribs 64.

Each of the members 6, (see Fig. 4), is formed with a pair of half section pockets or grooves 65 arranged in pairs and which may be shaped, as shown in Figs. 4 and 5, in which the said grooves are shown as diverging from their outer or entrance end, or they 15 may be made converging as shown in Fig. 6. Each section 6 is also formed with a drain groove 67 that extends from the top thereof to near the bottom at which point it extends laterally to form a discharge 20 through the front face of the anchor and the said drain grooves each communicate with the staple pockets or grooves 65 so as to drain them.

11 designates the wire strands of the 30 fencing.

What I claim is:

1. In a reinforced concrete post, a fence wire holding device embedded in the post body with one edge extended through the 35 said body, means mounted in the said face of the said holding device for receiving and supporting the fence wire strands, the said wire holding device consisting of an anchor plate embedded in one face of the cement post and having a series of staple receiving and holding sockets in its front edge, fence

wire holding staples rigidly held in the said plate, the said staple holding sockets being arranged in pairs and divergently disposed relatively to each other, said anchor plate 45 having a water draining channel that extends lengthwise thereof and discharges through the lower front face of said anchor plate, said draining channel having communication with the staple holding sockets. 50

2. In a reinforced concrete post, a fence wire holding device embedded in the post body, with one edge exposed through said body, said wire holding device consisting of a pair of metallic plate sections in face 55 contact with each other and having opposing matching corrugations to form staple receiving grooves, said plate sections having a longitudinal water draining groove in communication with said staple receiving 60 grooves and delivering to the outside of the post.

3. In a reinforced concrete post, a fence wire holding device embedded in the post body with one edge exposed through said 65 body, said wire holding device comprising a pair of plate members having opposing matching corrugations forming staple receiving grooves, each of said plates having a longitudinal rib on its outer side face adjacent to the rear edge of the plate, said plates having transverse apertures, tie wires passed through said apertures and bent substantially parallel to said plates to secure said plates together, said plates having reduced projections at their lower ends, and a securing member wrapped around said projections. 75

JAMES PETER KIMBLE.
